Primary Examiner — Michael A. Pratt(74) *Attorney, Agent, or Firm* — Volpe and Koenig, P.C.(57) **CLAIM**

I claim the ornamental design for a jet regulator, as shown and described.

DESCRIPTION

FIG. 1 is a top plan view of a jet regulator in accordance with my design;

FIG. 2 is a top, front perspective view thereof;

FIG. 3 is a bottom plan view thereof;

FIG. 4 is a front, bottom perspective view thereof;

FIG. 5 is a front elevational view thereof;

FIG. 6 is a left side elevational view thereof;

FIG. 7 is rear elevational view thereof; and,

FIG. 8 is a right side elevational view thereof.

The broken lines in the drawings depict portions of the jet regulator that form no part of the claimed design.
